Gordon H. Caskey, Seattle, Wash., assignor of one one-hundredth to Lydia Martin, one one-hundredth to W. T. Weaver, four one-hundredths to Ted Stanley Hudziak, one one-hundredth to Vivian Miller, one one-hundredth to Willma Griffin, all of Seattle, Wash., and one one-hundredth to Olive Leever, Vancouver, Wash.

Application November 27, 1948, Serial No. 149,863

Term of patent 7 years

(Cl. D45—4)

To all whom it may concern:

Be it known that I, Gordon H. Caskey, a citizen of the United States, and a resident of Seattle, in the county of King and State of Washington, have invented a new, original, and ornamental Design for a Combined Bracelet and Container for Cosmetics and Coins, of which the following is a specification, reference being had to the accompanying drawing, forming a part thereof.

Fig. 1 is a front elevational view of a combined bracelet and container for cosmetics and coins showing my new design, the charm elements being slightly in perspective.

Fig. 2 is a top edge view of the same.

I claim:

The ornamental design for a combined bracelet and container for cosmetics and coins, substantially as shown.

GORDON H. CASKEY.
